CLAIM

The ornamental design for a connector plug for computer port, as shown and described.

DESCRIPTION

FIG. 1 is a top, left, rear perspective view of a connector plug for computer port showing our new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a rear elevational view thereof; and,

FIG. 7 is a front elevational view thereof.

The broken lines in the figures represent portions of the connector plug for computer port which form no part of the claimed design.
